CARPET.

No. 15,863.

Patented Feb. 24, 1885.

UNITED STATES PATENT OFFICE.

HENRY HUNT, OF GREENVILLE, NEW JERSEY, ASSIGNOR TO THE HART-FORD CARPET COMPANY, OF HARTFORD, CONNECTICUT.

DESIGN FOR A CARPET.

SPECIFICATION forming part of Design No. 15,863, dated February 24, 1885.

Application filed January 14, 1885. Term of patent 7½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

Various large symmetrical figures of conventional flower and rosette forms are carried on inconspicuous angular stems with conventionalized leaf figures and irregular right-lined figures having dotted ornamentation, all as clearly shown in the photograph. 15 20

I claim—

The design for a carpet, substantially as shown and described.

HENRY HUNT.
